UNITED STATES PATENT OFFICE

114,122

DESIGN FOR AN OCEANPLANE

James V. Martin, Hempstead, N. Y.

Application November 30, 1937, Serial No. 73,279

Term of patent 14 years

To all whom it may concern:

Be it known that I, James V. Martin, a citizen of the United States, residing at the town of Hempstead, in the county of Nassau and the State of New York, have invented a new, original, and ornamental Design for an Oceanplane, of which the following is a specification, reference being had to the accompanying drawings, forming part thereof.

Fig. 1 is a plan view looking down upon my design.

Fig. 2 is a view in side elevation looking at the port side of one of the two hulls of my design.

Fig. 3 shows what my oceanplane design looks like in front elevation, and

Fig. 4 is a view in perspective looking upwardly in combined front and side aspect.

I claim:

The ornamental design for an oceanplane, as shown.

JAMES V. MARTIN.
